(57) **CLAIM**

The ornamental design for a shoe, as shown and described.

DESCRIPTION

FIG. 1 is a front perspective view of a shoe showing my new design;

FIG. 2 is a side view thereof;

FIG. 3 is a top view thereof;

FIG. 4 is an opposite side front perspective view thereof; and,

FIG. 5 is an opposite side view thereof.

The broken lines depicting the lace securing elements and the remainder of the shoe show features that form no part of the claimed design.

1 Claim, 5 Drawing Sheets

FIG. 1

FIG. 2

FIG. 3

FIG. 4

FIG. 5
